UNITED STATES PATENT OFFICE.

CHARLES G. AUCHTER, OF PITTSBURGH, PENNSYLVANIA.

DESIGN FOR A FORTUNE-TELLING GAME BOARD.

Application filed November 3, 1926. Serial No. 19,583. Term of patent 7 years.

To all whom it may concern:

Be it known that I, CHARLES G. AUCHTER, a citizen of the United States, residing at Pittsburgh, county of Allegheny, and State of Pennsylvania, have invented a new, original, and ornamental Design for Fortune-Telling Game Board, of which the following is a specification, reference being had to the accompanying drawing, forming part thereof.

Figure 1 is a plan view of the game board showing my new design. Figure 2 is a transverse section through the game board shown in Figure 1.

The shading and cross-hatching represents contrasting colors.

I claim:

The ornamental design for a fortune-telling game board, as shown.

CHARLES G. AUCHTER.
